I. N. Marquis, Inventor

By his Attorney Warren D. House,

UNITED STATES PATENT OFFICE.

ISAAC N. MARQUIS, OF KANSAS CITY, MISSOURI, ASSIGNOR TO THE STANDARD LIGHT COMPANY, OF SAME PLACE.

DESIGN FOR A VAPOR-BURNER.

SPECIFICATION forming part of Design No. 32,213, dated February 13, 1900.

Application filed January 13, 1900. Serial No. 1,392. Term of patent 14 years.

To all whom it may concern:

Be it known that I, ISAAC N. MARQUIS, a citizen of the United States of America, residing in Kansas City, in the county of Jackson and State of Missouri, have invented and produced a new and original Design for Vapor-Burners, of which the following is a specification, reference being had therein to the accompanying drawings, forming a part thereof.

Figure 1 represents an elevational view of a vapor-burner, showing my new design. Fig. 2 represents a plan view of the same.

The leading or material feature of my design consists in the configuration of the burner, as follows: The base portion B is in the form of a horizontal disk, the periphery of which is broken by a curved notch I and concentrically from the upper side of which rises the hollow cylindrical portion A, the periphery of which at one side and end adjacent to the disk B is provided with a horizontal slot C. Upon the underside of the disk B, at one side thereof and located below the slot C, is a radially-disposed partially-cylindrical horizontal boss G, which is connected by a vertically-disposed bridge E with the vertical

cylindrical jet portion D, located below the disk B and disposed concentrically therewith. The under side of the bridge E is obliquely inclined and has depending therefrom a U-shaped bracket portion F. The base B is provided with a center vertical hole H therethrough. The disposition of the portion D relative to the base B is such that a rectangular open space is formed by the two parts 35 in conjunction with the bridge E and the inner end of the boss G.

My invention is applicable to various styles of burners, such as use gas or oil.

Having described my invention, what I 40 claim as new, and desire to secure by Letters Patent, is—

The design for a vapor-burner as herein shown and described.

In testimony whereof I have signed my 45 name to this specification in the presence of two subscribing witnesses.

ISAAC N. MARQUIS.
